UNITED STATES PATENT OFFICE.

CARL EIBYE, OF DORCHESTER, MASSACHUSETTS, ASSIGNOR TO WILTBONCO MANUFACTURING COMPANY, OF JAMAICA PLAIN, MASSACHUSETTS, A CORPORATION OF MAINE

WATER-GAGE.

1,267,643.

Specification of Letters Patent. Patented May 28, 1918.

Application filed April 27, 1918. Serial No. 84,024.

To all whom it may concern:

Be it known that I, CARL EIBYE, a citizen of the United States, and a resident of Dorchester, in the county of Suffolk and State 5 of Massachusetts, have invented an improvement in Water-Gages, of which the following description, in connection with the accompanying drawings, is a specification, like characters on the drawings representing 10 like parts.

This invention relates to gages for indicating the water level in locomotive boilers and for other purposes.

The character of the invention may be 15 best understood by reference to the following description of an embodiment illustrating the invention shown in the accompanying drawings, wherein,—

Figure 1 is a front elevation of a gage 20 shown herein as illustrating the invention;

Fig. 2 is a rear elevation of the gage;

Fig. 3 is a longitudinal section taken on line 3—3 of Fig. 1;

Fig. 4 is a transverse section taken on 25 line 4—4 of Fig. 1; and

Fig. 5 is a transverse section taken on line 5—5 of Fig. 1.

Referring to the drawings, the gage shown therein comprises an elongated container 1 having necks 3 at opposite ends thereof tapped to receive pipes 5 and 7 for connection with a boiler or other receiver. The front of the container has an elongated aperture over which is seated a glass prism 9, a suitable gasket 11 being interposed between them. To enable the water level to be readily disclosed, the glass may be provided on its inner surface with usual facets 13 which render the water level clear cut and 40 distinct.

To secure the glass tightly to the container a frame 15 is provided formed to receive the glass and a portion of the container. To permit the visualization of the 45 water level through the glass, the frame may have an elongated aperture 17 opposite the elongated aperture of the container. A suitable gasket 19 may be interposed between the frame and the glass.

50 To press the container and frame toward each other, there are provided yokes 21 straddling the container and having terminals adapted to be connected with said frame. To accomplish this, the latter has

ears 23 projecting laterally from opposite sides thereof having eyes registering with eyes in said yokes. Pins 25 are adapted to project through said eyes and detachably connect the yokes with said ears. The upper ends of these pins may be bent to limit 60 downward movement of the pins as shown in Fig. 2.

Screw bolts 27 are tapped into the yokes and have ends adapted to bear against the back of the container. These screw bolts 65 may be set up to secure the parts together with the necessary tightness, and may be readily released when it is desired to open the yokes and substitute a new glass for an old one.

The features of the gage thus far described are similar to those shown in my application for Letters Patent of the United States, Serial No. 788,348, filed September 5, 1913. Some objection to this form of 75 gage has hitherto been experienced owing to the tendency of the portions of the frame at the sides of the sight aperture thereof, to spread if the screw bolts are set up to place the yokes under too great tension. This 80 distortion of the frame tends to increase the liability of the glass to crack and invites leakage. The sides of the frame and container of the gage shown in said application abut against each other substantially 85 at points 28 within the lines of tension α — α extending from the points of engagement of the screw bolts with the back of the container, to the centers of the pins 25. Obviously, when the screw bolts are tightened, 90 since the abutting points of the container and frame are within said lines, a moment of force will occur tending to pull the portions 15 α (Fig. 1) of the frame at the sides of its aperture outward, and the distortion 95 effect thereof will be greatest midway between the ends of the frame substantially on line 4—4 of Fig. 1.

One of the objects of the present invention is to prevent such distortion. To accomplish this the frame is provided with bearing elements typified herein in the form of ribs 29 which may conveniently be continuations of the ears 23. These ribs project rearward substantially to the back of 105 the container and the latter is provided with opposed ribs 31 for bearing engagement therewith. The opposed ribs on the frame

and container may be conveniently arranged in pairs corresponding to and on opposite sides of the yokes.

The ribs for the frame and container abut at points adjacent their rear ends on line $y-y$ and a substantial distance outward beyond the yoke tension lines $x-x$ referred to. Consequently, when the screw bolts are tensioned a strong moment of force will occur which, instead of spreading the portions of the frame at the sides of its sight aperture, will tend to draw said portions toward one another, thereby preventing distortion of the frame and preventing leakage and cracking of the glass.

The construction referred to not only prevents the distortion of the frame, but desirably contributes to the general strength of the gage. Also it eliminates the necessity for the bar shown in said application extending across and obstructing a portion of the sight aperture of the frame midway between the ends thereof. The improvement renders the entire length of the aperture available to disclose the water level.

Having described one illustrative embodiment of the invention without limiting the same thereto, what I claim as new and desire to secure by Letters Patent is:—

1. A gage comprising in combination, a container, a frame having a sight aperture, a glass between said container and frame, yokes straddling said container, pins entered through said yokes and frame, screws tapped into said yokes engaging the back of said container, and ribs on said frame and container bearing against each other at points outward beyond the lines of strain from said screws to said pins, to tend to draw the portions of the frame at the sides of said aperture inwardly.

2. A gage comprising in combination, a container, a frame having a sight aperture, a glass confined between said frame and container, a yoke, means connecting said yoke and frame, screw means coöperating with said yoke to draw said container and frame toward each other, and elements for said frame and container bearing against each other at points to cause said screw means

to tend to draw the portions of the frame at the sides of said aperture inwardly.

3. A gage comprising in combination, a container, a frame having a sight aperture, a glass confined between said frame and container, a yoke, means connecting said yoke and frame, screw means coöperating with said yoke to draw said container and frame toward each other, and means coöperating with said parts tending to draw the portions of the frame at the sides of said aperture inwardly.

4. A gage comprising in combination, a container, a frame having a sight aperture, a glass confined between said frame and container, means for pressing said frame and container toward each other, and means coöperating therewith tending to draw the portions of said frame at the sides of said aperture toward each other.

5. A gage comprising in combination, a container, a frame having a sight aperture, a glass confined between said frame and container, means for pressing said frame and container toward each other tending to spread the portions of said frame at the sides of said aperture, and means to prevent such spreading action.

6. A gage comprising in combination, a container, a frame having a sight aperture, a glass confined between said frame and container, a series of yokes, means coöperating therewith for pressing said container and frame toward each other, and opposed abutments on said frame and container adjacent said yokes to prevent spreading of the portions of the frame at the sides of said aperture.

7. A gage comprising in combination, a container 1, a frame 15 having a sight aperture 17, a glass 9 confined between said frame and container, securing means 21, 23, 25, 27 for drawing said frame and container toward one another, and means 29, 31 to prevent said securing means from distorting said frame.

In testimony whereof, I have signed my name to this specification.

CARL EIBYE.
